P. I. WOLD

VACUUM TUBE OSCILLATOR CHRONOMETER

Filed Aug. 24, 1920

Inventor:
Peter I. Wold.
by C. A. Sprague. Atty.

UNITED STATES PATENT OFFICE.

PETER IRVING WOLD, OF EAST ORANGE, NEW JERSEY, ASSIGNOR TO WESTERN ELECTRIC COMPANY, INCORPORATED, OF NEW YORK, N. Y., A CORPORATION OF NEW YORK.

VACUUM-TUBE OSCILLATOR CHRONOMETER.

Application filed August 24, 1920. Serial No. 405,844.

To all whom it may concern:

Be it known that I, PETER IRVING WOLD, a citizen of the United States, residing at East Orange, in the county of Essex, State of New Jersey, have invented certain new and useful Improvements in Vacuum-Tube Oscillator Chronometers, of which the following is a full, clear, concise, and exact description.

10 This invention relates to a vacuum tube oscillator chronometer and more particularly to a method of increasing the constancy of certain operating characteristics of such apparatus.

15 An object of the invention is to utilize an oscillation generator of the type in which the frequency of oscillation is determined by the constants of a freely oscillating circuit, to perform mechanical work.

20 Another object of the invention is to provide a chronometric system of exceptional constancy and accuracy by the expedient of using as the actuating means for the time controlling element an oscillation generator of the type in which the frequency is set by the constants of a freely oscillating circuit.

25 A further object of the invention is to provide an oscillator chronometer of the above mentioned type having a high degree of constancy.

30 The inventor has discovered that the comparative constancy of the oscillation generator of the type disclosed, which is distinguished broadly from other types by the feature that its frequency is determined by the constants of an oscillation circuit associated therewith, fits such a generator for use as the driving means in a chronometric system, and that an accuracy and constancy heretofore unattained could be made possible by such use.

35 The type of generator proposed has become familiar through use as a generator of high frequency currents in radio transmission and this type is adaptable to the use proposed, that is, in a chronometric system, in any one of its generic forms. If the input and output circuits of an amplifying or 40 repeating device are related in such a manner that energy is fed back from the output to the input circuit, it is possible to develop oscillations if the physical and electrical constants of the amplifier or repeater 45 and the electrical constants of the asso-

ciated circuits are properly proportioned. A coupling which may be inductive or electrostatic may be used for this purpose and in the case of vacuum tube amplifiers, this may even be effected through the internal 60 capacity between the elements or electrodes of the tube itself. It is desirable for certain purposes that such vacuum tube circuits include an oscillatory tuned circuit. Such a tuned circuit may be connected in 65 the input or output circuit or in common in both of these circuits. If the tuned circuit comprises the principal portion of the impedance elements in the tube circuits it may be made to substantially determine the frequency of the oscillations generated. It is therefore possible to make the generated frequencies substantially as desired by 70 properly adjusting the constants of this circuit. 75

The inherent advantage of the use of this type of actuating means for the time controlling elements are at once apparent when it is noted that there is an entire absence of moving structure and that the frequency 80 depends on the value of the electrical constants of inductance and capacity, which quantities are readily capable of adjustment for different frequencies, and with a given frequency, are or can be made 85 remarkably stable and invariable under the conditions imposed by use in this system.

Oscillation generators of the type described have been made to operate efficiently at a frequency as low as one cycle in ten 90 seconds and as high as a hundred million cycles a second. It has been difficult to design an oscillator at the lowest frequencies having an approximately pure sine wave form since it is ordinarily necessary when 95 attaining oscillations of frequencies less than one thousand or two thousand per second to use inductances containing iron, although it has been shown in Scriven Patent 1,354,657 November 2, 1920, how this may 100 be accomplished by utilizing the difference frequencies resulting from the interaction of two sets of oscillations of higher frequency. In the present invention the employment of iron core inductances is not 105 only not attended by any disadvantages, but even has a positive advantage in that it makes possible a more efficient use of the device for the performance of mechanical work. 110

The invention in its second aspect relates to the means suggested above for increasing the constancy of frequency of the generator. As is well known, the equation which expresses the natural frequency of a freely oscillating circuit contains the product $L C$, which letters designate respectively the inductance and capacity of the oscillating circuit, these being the principal variable quantities concerned. If this product can be kept constant, the frequency of the circuit will be constant.

That the product may be constant, under certain conditions, even though the component quantities L and C are varying, is obvious. It is the essence of this invention to so choose the inductance and capacity containing elements that they vary, under similar conditions of physical change, in an opposite sense so that their product remains substantially constant.

For a more detailed disclosure of the invention, reference is made to the description which follows, taken in connection with the accompanying drawing, Figure 1 of which shows, in diagrammatic form, one embodiment of the invention; Fig. 2 shows an alternative arrangement of the mechanical elements actuated by the oscillator;

Fig. 3 shows a method of interposing an electromagnetic relay between the oscillator and the actuated mechanism; and

Fig. 4 shows an arrangement similar to Fig. 3 but having the electromagnetic relay replaced by a vacuum tube amplifier.

In Fig. 1 there is shown a circuit arrangement of an oscillation generator, such as is disclosed in Hartley Patent 1,356,763, October 26, 1920, although other types may equally well be used, the essential feature being a freely oscillating circuit and a coupling between the grid and the space current circuits of the generator. A highly evacuated tube 1 contains the usual hot filament 45 cathode 2, plate electrode 4 and impedance controlling grid 3. The filament is energized by a direct current source 5 in circuit with which is the filament resistance 6. A two-part inductance 7, 7' is connected to a 50 variable condenser 8 to form a closed tuned circuit, one terminal of the condenser 8 being connected through space current source 9 to plate 4, while the other terminal is connected to grid 3 preferably through a source 55 10 which serves to keep the grid at a potential which is negative relative to that of the cathode. An intermediate point of the two part inductance is connected to the cathode. A variable resistance 11 may be inserted in 60 the space current circuit in order to provide means for slight adjustment of oscillation frequency. Altho in general the constants of the freely oscillating circuit determine the frequency very slight changes may be effected by means such, for example, as the above.

The inductances 7 and 7' may be inductively related but this is not essential. The tube 1 and its associated circuits as described constitute an oscillation generator which serves to produce oscillations of a frequency determined by the constants of the closed tuned circuit. In certain applications of this generator, as for example, in chronometric applications where such a low frequency as one cycle per second may be desirable the inductances 7 and 7' would ordinarily have iron cores. The presence of the magnetic core results in the introduction of higher frequency harmonics in the generated wave, and the wave form is accordingly of insufficient purity for certain other applications which require higher frequency, but the constancy of the frequency is not affected thereby as long as the product $L C$ does not change and, since the frequency alone enters as an element in the equation of efficiency of the arrangement of this invention, the presence of the iron does not affect the efficient operation of the device. It does, in fact, make possible an efficient use of the output current in operating the mechanical movement shown. This mechanical movement is shown as an element of a clock; the coils 7 and 7' with their common iron core functioning, with the armature 13 and the toothed wheel 12 as an escapement device through which the stored energy of the coil spring 14 may be applied to actuate the hands of the clock 31 through a train of mechanical movements according to principles well known in the art of horology the spring 15 serves to retract the armature 13 when the magnetic pull of the coils 7 and 7' is reduced to zero. Although the attractive power of an electromagnet depends greatly on the presence of a magnetic core, as is well known, such core is not essential and this invention should be understood to embrace the use of an oscillation generator of any frequency whatever and with or without magnetic parts, to perform mechanical work. In Fig. 2 the coils 7 and 7' with the common iron core function with the armature 13 as a reciprocating motor to impart by means of lever 16 and pawls 17 and 18 a step-by-step motion to the toothed wheel 12 and therethrough to the hands of the clock. In this arrangement the spring 14 shown in Fig. 1 is not used, the energy of the electrical oscillations being converted and applied directly to actuate the hands of the clock.

Although the means of the invention has been shown as operating a stepping mechanism of a clock, it should be noted that considerable expenditure of energy is required to perform this function and that it may, under certain circumstances, be desirable to use a smaller generator unit, especially since a generator of a smaller size is inherently more accurate than the larger sizes. Fig. 3

shows an arrangement of the invention to provide for this case. The armature 13 when attracted to the electromagnet pole causes a circuit comprising a battery 22 and an electromagnet 23 to be closed through contacts 20 and 21 thus energizing the electromagnet 23 and attracting the armature 24. The armature 24 and lever 25 take the place of the armature 13 and lever 16 of Fig. 2 and 10 may be adapted to impart a step-by-step motion to a clock mechanism in the manner there shown. The relay means in the above is essentially an amplifying means intermediate between the time controlling circuit 15 of the invention and the mechanical element of the stepping mechanism. In place of the amplifying means as above a vacuum tube amplifier may equally well be used to perform this function and its application in a 20 system such as that shown is illustrated in Fig. 4. Coil 26 is inductively coupled to the coils 7 and 7' and serves to translate the current variations therein to potential variations on the grid of the vacuum tube 27. 25 The plate circuit of the vacuum tube contains the electromagnet 23, and energizing battery 28 which is connected to the filament of the vacuum tube through a choke coil 29 and a condenser 30 which serves to prevent 30 the passage of the battery current through the windings of the electromagnet 23. Armature 24 and lever 25 are associated with electromagnet 23 as shown also in Fig. 3 and may be adapted to actuate the hands of the 35 clock in the manner described in connection therewith. The current oscillations in coils 7 and 7' are reproduced by the action of the vacuum tube 27 with amplified energy in the electromagnet 23 and thereby caused 40 to impart to the armature 24 and lever 25 a periodic motion which is transmitted to the clock mechanism as already described.

It remains to describe the means of the 45 invention to insure a high degree of constancy of the system disclosed. As has been pointed out, the accuracy of this arrangement as a time device depends chiefly on the constancy of the product of L and C. These 50 ordinals are being used to designate respectively the inductances 7 and 7', considered as one inductance, and capacitance 8. A higher constancy than would ordinarily be expected can be obtained by having the capacity and inductance change in opposite directions for any given physical change. The chief changes to be considered are temperature changes and the effects of ageing. The method of this invention should effectively compensate for these changes.

60 In the case of iron core inductance elements, which would ordinarily be used in chronometric systems, the permeability, and therefore the inductance, decreases slightly as the temperature increases. In other 65 words, an iron core inductance has a nega-

tive temperature coefficient. A resistance shunted by a capacity is equivalent in effect in a circuit to a negative inductance having a value given by the equation $-L = CR^2$ in which R designates the resistance and C the shunting capacity. Accordingly, the 70 temperature coefficient of an inductance element which has associated with it a resistance and a shunt capacity will be partially determined by the temperature coefficient of 75 said resistance and capacity and it is possible to produce inductances having either a negative or a positive temperature coefficient. An inductance having a positive temperature coefficient will increase with increase of temperature, the converse being 80 true in the case of an inductance having a negative temperature coefficient.

In regard to condensers, one of the most 85 constant and reliable forms is the dry stack mica condenser. These have a positive temperature coefficient which may be in the neighborhood of a .00007 per degrees Fahrenheit and the coefficient is fairly constant over a wide range. The coefficient will vary 90 considerably with different condensers or different types of condensers and some may even have a negative coefficient. Taking into account the possibility of using other dielectric materials, however, it is possible 95 to obtain a condenser having any temperature coefficient within the limits of variation between the reactive constants of different inductance elements, still further it would not be very difficult to obtain one 100 which would just neutralize that of the coil. In the above the meanings of positive and negative temperature coefficients are readily 105 derivable by analogy from the meanings as applied to inductances.

As regards the effect of ageing, it has been 110 found that generally mica condensers increase slightly in capacity with age, while inductances decrease slightly so that the changes may be made to offset each other, thus compensating for changes that occur over a long interval of time.

Since condensers can readily be obtained 115 which have either a positive or a negative temperature coefficient, as has been pointed out, it is clear that a condenser may be selected which will compensate for the negative or positive temperature coefficient of an inductance. Accordingly, the method proposed 120 is equally applicable for an oscillation generator of all frequencies, or for any tuned circuit in which it is desired that the frequency should be automatically regulated.

It should be noted that the actuation of 125 the armature 13 necessarily involves a change in the reluctance of the magnetic circuit of the coils with attendant variation in inductance and oscillation frequency, and it might seem that there would thereby be introduced 130 an element of uncertainty that would nega-

- tive the results otherwise reached, but it may be pointed out that the change in frequency produced thereby occurs only within a single cycle and results only in a distortion of the 5 wave form without affecting its periodicity. In other words, the frequency of this reluctance variation is the same as that of the frequency of oscillation, and is therefore without effect thereon.
- 10 Although the frequency is dependent almost wholly on the value of L and C in the oscillatory circuit, there are other variable factors in such a vacuum tube oscillator. For example during its life the internal impedance of the tube would change slightly, in general increasing with time. Such a change could be taken care of with more or less accuracy by having a resistance such as 11 in series with the plate which could be changed 15 gradually with time, the clock mechanism operating to bring about this change or the change may be accomplished by hand if desired at definite intervals, the change, of course, being in the reverse direction to the 20 change within the tube. For extreme accuracy, it would, of course, be necessary to attain as high a constancy as possible for other factors such as the filament heating current and the plate voltage, but it should 25 be noted that the frequency of the oscillator is only very slightly affected by changes in these factors even as compared with the effect of the factors already mentioned, which are themselves very slight.
- 30 35 Although the invention has been disclosed or applied to a specific mechanical system it may equally be used, as has been suggested, to perform mechanical work in many other applications as, for example, to actuate a 40 relay contact. The invention should accordingly not be considered as so limited but only by the breadth of the appended claims.
- What is claimed is:
1. The combination of a mechanically driven means and a driving means therefor, said last mentioned means comprising an oscillation generator of that type in which the frequency is determined by the natural frequency of a freely oscillating circuit.
  2. The combination of a mechanically driven means and a driving means therefor comprising an oscillation generator of the electrical discharge type, the frequency of which is determined by the natural frequency of a freely oscillating circuit forming a part thereof.
  3. In combination, a mechanically driven means and a driving means therefor comprising an oscillation generator of the vacuum tube type, the frequency of which is determined by the natural frequency of a freely oscillating circuit.
  4. The method of actuating a driven means at a uniform speed, which comprises actuating said means by an oscillation generator of the vacuum tube type, the frequency of which is determined by the natural frequency of a freely oscillating circuit.
5. The method of regulation and actuation of a driven means which comprises the steps of actuating said means by an oscillation generator of the vacuum tube type and regulating the speed thereof by adjusting the natural frequency of the oscillatory circuit of said oscillation generator. 75
6. In a timing device, in combination, a time controlling element and an actuating means therefor comprising an oscillation generator of the vacuum tube type, the frequency of which is varied by varying the natural 80 frequency of its associated oscillatory circuit.
7. In a timing device, in combination, a time controlling element, a mechanical actuating means therefor and an oscillation generator of the vacuum tube type having a tuned oscillatory circuit associated therewith, the natural frequency of which determines the frequency of said oscillation generator, the inductance coils of said tuned circuit 85 being so related to said mechanical actuating means that said means is actuated in accordance with the frequency of the current of said inductance. 90
8. The method of increasing the constancy 95 of an oscillatory circuit which consists in selecting inductance and capacity elements of said circuits of such types respectively that their constants change in opposite directions for a given physical change whereby the 100 product of inductance and capacity is kept substantially constant.
9. The method of increasing the constancy of frequency of an oscillation generator which consists in combining in the 105 oscillatory circuit thereof, inductance and capacity elements having oppositely varying characteristics under given physical changes.
10. The combination as recited in claim 7, 110 in which the inductance and capacity elements in said oscillatory circuit are of such types that their respective constants vary in opposite directions under given physical changes. 115
11. The method as recited in claim 4, which includes the additional step of choosing inductance and capacity elements having such characteristics that their variations under the given physical changes mutually compensate for each other. 120
12. A tuned circuit comprising inductance and capacity elements having oppositely varying characteristics under given physical conditions whereby these variations mutually compensate for each other. 125
13. An oscillator comprising a three element thermionic discharge device associated with a tuned circuit of the type set forth in claim 12. 130

14. A mechanism, an electrical oscillating device having a tuned circuit for determining the frequency of its oscillations and means whereby said electrical device drives 5 said mechanism.
15. In combination, a driven means and a driving means therefor, said driving means comprising a frequency determining circuit having inductive and capacitive elements, 10 said elements having oppositely varying characteristics under given physical conditions whereby these variations mutually compensate for each other.
16. An electrical system comprising a circuit including a plurality of impedance elements, said elements having impedances of opposite signs and means for causing the effect on said circuit of any variation in the characteristics of one element to be compensated by a corresponding variation in the characteristics of another element having impedance of the opposite sign.
17. In combination, an oscillation generator of that type in which the frequency 25 is determined by the natural frequency of a freely oscillating circuit and a mechani-
- callly driven means, the actuating energy therefor being derived from said oscillating circuit.
18. The method of actuating a driven 30 means at a uniform rate, which consists in actuating said means by an oscillation generator, the frequency of oscillation being determined by the constants of an electrical circuit and the actuating energy for the 35 driven means being derived from said circuit.
19. In a timing device, in combination, a time controlling element, a mechanical actuating means therefor, and an oscillation 40 generator of the vacuum tube type having a tuned oscillatory circuit associated therewith, the natural frequency of which determines the frequency of said generator, the inductance coil of said oscillator circuit 45 being so related to said mechanical actuating means that the operating energy therefor is derived from said inductance coil.

In witness whereof, I hereunto subscribe my name this 18 day of August A. D., 1920.

PETER IRVING WOLD.
